UNITED STATES PATENT OFFICE.

ARTHUR L. STANFORD, OF CHICAGO, ILLINOIS.

RAIL-ANCHOR.

1,108,635.

Specification of Letters Patent. Patented Aug. 25, 1914.

Application filed March 21, 1914. Serial No. 826,294.

To all whom it may concern:

Be it known that I, ARTHUR L. STANFORD, a citizen of the United States, residing at Chicago, in the county of Cook and State 5 of Illinois, have invented certain new and useful Improvements in Rail-Anchors, of which the following is a specification.

This invention relates to an anchor intended and adapted for use in connection 10 with railway rails for the purpose of preventing a longitudinal creeping of said rails.

The objects of the present invention are to provide an anchor of the character specified which is capable of being formed of two 15 parts; one of which constitutes the body portion together with a fixed gripping jaw and a tie abutment and the other of which consists of a movable gripping jaw which finds a mounting within the body portion.

20 A further object of the invention is to angularly dispose the movable gripping jaw with respect to the under face of the base of the rail whereby when the said movable jaw is forced into position it will exert a 25 pressure upon the body of the anchor drawing it toward and across the under face of the rail base, thus efficiently locking the said anchor to the rail.

A further object of the invention is to 30 form the auxiliary gripping jaw in a manner whereby the acting portion thereof will extend diagonally across the upper edge of the base of the rail and lie upon each side thereof and at an angle to said edge whereby 35 when the jaw is forced into position it will be forced into engagement with said edge.

A further object of the invention is to 40 so configure the acting portion of the movable jaw as to tighten its engagement with the edge of the rail base automatically, when 45 the rail tends to creep.

A further object of the invention is to so arrange and construct the body of the anchor as to permit of its ready and easy 50 insertion upon the rail and removal therefrom.

A further object of the invention is to eliminate and avoid the use of threaded members in connection with the anchor.

55 The invention further consists in the features of construction and combinations of parts hereinafter described and claimed.

In the drawings: Figure 1 is a view showing the anchor with the parts in the position 55 they assume at the initial installation upon the rail base and showing the body of the

anchor in cross section; Fig. 2 is a view similar to Fig. 1 showing the position assumed by the parts when the anchor is locked or in operative position and showing a 60 slightly modified construction of movable gripping jaw and mountings therefor; Fig. 3 is a plan view with the fixed gripping jaw in section; Fig. 4 is a perspective of the anchor with the rail removed; and Fig. 5 65 is a section taken on line 5—5 of Fig. 2 looking in the direction of the arrows.

The devices of the art to which the present invention relates, namely, rail anchors, are intended and adapted to hold the rail 70 against a creeping movement which is imparted to the rail by the passage of the rolling stock there over. This creeping results in a disorganization of the track and it is well 75 recognized in railroad circles that such creeping is undesirable and should be eliminated.

Referring now to the drawings, the device of the present invention consists of a body 6 which comprises a floor 7 that extends beneath and is in contact with the lower face 8 of the rail base. The floor 7 terminates at one end in what may be termed a fixed gripping jaw 9. This gripping jaw, as shown in Fig. 3, extends parallel with a side edge 85 of the rail base and from edge to edge of the anchor. This gripping jaw 9 includes an overhanging portion 10 that engages the upper face of the rail base, and upon that side of the anchor on which is located the 90 fixed gripping jaw is also located a tie abutment 11. In the construction shown, this fixed gripping jaw and tie abutment are formed integral with the body of the anchor, and in the construction shown vertically 95 depending flanges 12 are provided which depend from the floor 7 of the body. At the opposite end from that at which is located the fixed gripping jaw and rail abutment is a sleeve 13 which is also in the construction 100 illustrated formed integral with the body. The bore 14 of this sleeve is disposed at an angle to the floor of the body which angle in the construction illustrated is approximately 45 degrees although a variance is contemplated in this precise angle as will appear from further description. This sleeve serves as a mounting for what may be termed a 105 movable gripping jaw 15. This gripping jaw comprises a stem 16 terminating in an eccentric head 17, the latter being the acting portion of the gripping jaw. The stem

110

projects beyond the sleeve and such projecting portion 18, if desired, may be of a polygonal formation, although the particular shape is optional with the manufacturer.

As will be observed from the drawing, the eccentric head 17 is so located as to extend diagonally across and lie upon each side of the upper edge 19 of the rail base and when the device is initially positioned, as in Fig. 1, the low portion of the eccentric head is toward such edge and there is a slight clearance between the head and the edge of the rail base. This clearance should be sufficient to allow for the variations in the size of similar rail bases, and enable the device to be readily and easily positioned upon bases varying somewhat in size.

In initially positioning the device the movable gripping jaw 15 is not in place and the body of the anchor is slipped into position about the rail base in an obvious manner. The movable gripping jaw is then placed in position as in Fig. 1, and the stem 16 is turned by means of any suitable tool, this turns the eccentric head and brings it into a gripping engagement with the edge 19 of the rail base as in Fig. 2. When this has been done said head can be struck a sharp blow at a point opposite from the point of engagement between the head and edge 19 and thus drive the head securely into engagement with the said edge.

As heretofore stated, the head is positioned at an angle to the floor of the body of the anchor and at an angle to the edge 19 of the rail base. Owing to such angular disposition the pressure exerted by the forcing of the movable gripping jaw into position will be in the direction of the arrow in Fig. 1. A strain in this direction will tend to force the body of the anchor toward the bottom face of the rail base and at the same time force it across and transversely of the bottom face of the rail base, the latter movement bringing the fixed gripping jaw 9 into tight engagement with that edge of the rail against which it abuts, therefore by tightening the movable gripping jaw into engagement with the upper edge 19 of the rail base, an engagement will be brought about between the lower face of the rail base and the floor of the anchor as well as between the fixed gripping jaw and that portion of the rail base against which it abuts.

It will be observed that both the fixed gripping jaw and the tie abutment are straight, the tie abutment resting squarely against the side of the tie and the fixed gripping jaw extending parallel and engaging for its full length with the edge of the rail base. With this construction a turning or canting movement of the anchor is not permitted. Therefore, after the anchor is once positioned it is not intended that it shall be turned or twisted from such posi-

tion. It will be remembered, however, that the head 17 is eccentric, therefore, after the parts are positioned if there is sufficient force exerted to cause the rail to slide through the anchor such movement of the rail will turn or revolve the eccentric head to bring it into tighter engagement with the edge 19 of the rail base thus drawing the floor and the fixed jaw 9 into tighter engagement with the rail and thus the anchor is automatically given a tighter hold upon the rail as the creeping strains increase. This feature of the invention will, it is thought, be clearly understood by referring to Fig. 5 of the drawings in which the direction of movement of the rail is indicated by the arrow.

I deem it advisable to make the head 17 of a harder metal than the metal of the rail whereby when the head is driven into place it may embed into the edge 19 of the rail. While this feature of the device is altogether practical it is not essential to the efficient operation of the anchor, and may be employed or not according to the judgment of the manufacturer.

In Fig. 2 there is illustrated a slight modification of the form shown in the remaining figures of the drawing. In this modification the stem 16 is tapered and the walls of the bore of the sleeve 14 are tapered in conformity thereto. In this form, owing to the taper of the stem and the taper of the socket in which the stem seats, a locking of the stem in place can be brought about by a blow struck on the end of the head which forces the stem into wedging engagement with the socket, thus securely and firmly combining all of the parts together at the initial installation of the device. As stated, the tie abutment rests squarely against the tie and the fixed gripping jaw extends parallel, and is in contact for its entire length with the edge of the rail base against which it abuts and with the movable locking jaw locked in position by driving it into wedging engagement with the walls of the socket the anchor is locked in a manner to efficiently prevent creeping, for if any strains should come upon the rail tending to make it creep the tendency of such strains would be to cause the anchor to turn but such turning is impossible owing to the arrangement of the tie abutment and fixed gripping jaw, and thus this strain will be immediately resisted and the creeping checked.

The arrangement of the parts is such as to eliminate a movement of the rail through the anchor unless a breakage of the anchor should occur. It will be noted that although the head is angularly disposed, it, nevertheless, forms and constitutes a rail engaging surface which contacts with the rail base at an opposed point from the fixed gripping jaw. There are thus provided jaws which

are oppositely disposed from one another as is necessary and essential in anchors of this type and at the same time one of the jaws is so arranged as to exert a pressure tending 5 to pull the anchor toward and across the lower face of the rail base making substantial contact between the rail and the anchor.

I claim:

1. In a rail anchor the combination of a 10 body portion embodying a floor underlying the rail, a tie abutment, a gripping jaw fixed with respect to the body portion, a rotatable member oppositely disposed from the fixed gripping jaws and having its axis of rotation at an angle to the floor of the body portion and forming the movable gripping jaw of the anchor, said rotatable member extending diagonally across the upper edge of the rail base with its acting face arranged to 15 be brought into engagement with such edge and a mounting for said member carried by said body, substantially as described.

2. In a rail anchor the combination of a 20 body portion embodying a floor underlying the rail, a tie abutment, a rail gripping jaw fixed with respect to said body portion, a rotatable member embodying an eccentric head, said member being oppositely disposed from the fixed jaw and constituting a movable gripping jaw, said member having its 25 axis of rotation at an angle to the floor of the rail base, said head extending diagonally across the upper edge of the rail base and arranged to be brought into engagement 30 with such edge and a mounting for said member carried by said body portion, substantially as described.

3. In a rail anchor the combination of a 35 body portion embodying a floor underlying the rail, a tie abutment, and a fixed gripping jaw formed integral with the body portion, a rotatable member embodying an eccentric head and forming a movable gripping jaw and oppositely disposed from the fixed gripping jaw, said head being angularly disposed 40 with respect to the floor of the body portion and extending diagonally across the upper edge of the rail base and arranged to be brought into engagement with such edge and 45 a mounting for said rotatable member integral with said body, substantially as described.

4. In a rail anchor the combination of a 50 body portion embodying a floor underlying the rail, a tie abutment and a gripping jaw integral with the body portion and located at one end thereof, an angularly disposed

sleeve at the other end of the body, a stem rotatably mounted in said sleeve, an eccentric head on the stem, said head extending 55 diagonally across the upper edge of the rail base and arranged to be brought into engagement with such edge, said head constituting a movable gripping jaw, substantially as described.

5. In a rail anchor, the combination of a 60 body portion embodying a floor underlying the rail, a tie abutment and a fixed gripping jaw formed integral with said body portion, a stem movable with respect to the body 65 portion and oppositely disposed from the fixed jaw and forming a movable gripping jaw, said stem being diagonally disposed with respect to the floor of the body portion, the outer end of the stem extending diagonally across and in engagement with the upper edge of the rail base and a sleeve integral with said body and forming a mounting for said stem, substantially as described.

6. In a rail anchor, the combination of a 70 body portion embodying a floor underlying the rail, a tie abutment on said body portion, a fixed gripping jaw on said body portion, a stem oppositely disposed from the fixed gripping jaw and forming a movable gripping jaw, said stem extending across the 75 upper edge of the rail base diagonally with respect to said edge and to the floor of the body whereby the pressure exerted by said movable jaw tends to move the body simultaneously against and across the bottom face of the rail base, and a mounting for said stem disposed parallel to said stem, substantially as described.

7. In a rail anchor, the combination of a 80 body portion embodying a floor underlying the rail, a tie abutment and a fixed gripping jaw on the body portion, a rotatable member oppositely disposed from the fixed gripping jaw, said rotatable member engaging 85 the upper portion of the rail base and exerting pressure at an angle to the floor of the body portion whereby the pressure of said jaw tends to move the body simultaneously against and across the body face of the rail 90 base, a seat for said rotatable member, said member and seat being configured to enable a wedging engagement therebetween when the member is driven into said seat, substantially as described.
